UNITED STATES PATENT OFFICE.

WILLIAM R. KINNEAR, OF NEW CASTLE, PENNSYLVANIA.

ANNEALING OR OTHER LIKE APPARATUS.

935,793.

Specification of Letters Patent.

Patented Oct. 5, 1909.

Application filed September 4, 1908. Serial No. 451,715.

To all whom it may concern:

Be it known that I, WILLIAM R. KINNEAR, a citizen of the United States, residing at New Castle, in the county of Lawrence and 5 State of Pennsylvania, have invented certain new and useful Improvements in Annealing or other Like Apparatus, of which the following is a specification.

This invention relates primarily to annealing 10 in closed receptacles, and particularly to that class of annealing which requires the use of annealing boxes made in separable parts, but obviously some features of my invention are applicable to other industrial 15 processes wherein a hermetic seal is advantageous.

The object of the invention is to provide a suitable apparatus for effectually sealing the receptacle against the ingress of air at 20 all times when the box is at a temperature that would induce objectionable oxidation of the material being annealed and at the same time permit the annealing box to be readily opened and closed when cold.

25 My invention consists in applying to the joint between the separable parts of the annealing box or other container in which metal objects are to be heated, a sealing medium that is capable of resisting the heat 30 to which the box is to be subjected and which will assume a fused or fluid state under heat without becoming volatile, and preferably one which will solidify and permit separation of the parts when cold.

35 My invention further relates to certain details of construction of an annealing box of the character described, whereby the supporting surface of the pan or tray is elevated to a plane above the walls of the surrounding 40 trough so that the trough will drain the supporting surface upon which plates are often placed wet from the pickling and rinsing bath and will not offer any obstruction to the removal of the annealed plates; also details of construction whereby the pan or tray 45 is supported above the oven surface, or other surface upon which it rests so as to permit circulation of air beneath it.

My invention will be fully understood 50 upon reference to the accompanying drawing, in which,

Figure 1 is a vertical sectional view of a common form of annealing box modified to adapt it for manipulation in accordance with 55 my present invention; Fig. 2 is a similar view showing the parts separated; Figs. 3

and 4 are views corresponding to Figs. 1 and 2, showing a modification. Fig. 5 is a view similar to Fig. 1 showing a modified construction of pan or tray. Figs. 6, 7 and 8 60 are respectively a plan view, a vertical longitudinal section, and a transverse section of a pan or tray further modified in construction.

A represents the pan or tray of an annealing box, such for instance as used for annealing sheets of metal, and B represents the cover. These parts are fitted together by setting the cover B upon the pan A within the flange C formed on the latter, and in 70 order to prevent free ingress of air, while permitting escape of air under internal expansion due to heat, the space between the cover and the flange C has heretofore been filled with some material such as sand, or 75 other granular or pulverulent substance.

According to my present invention, I supply an additional flange D which, with the flange C, makes a trough extending around the pan and into which trough the lower 80 edge of the cover may enter. In the trough I then place a material, preferably lead, which while solid at ordinary temperatures, fuses and becomes fluid under any temperature that would promote objectionable oxidation of the material being treated. When the box is introduced into the furnace, the sealing material in the trough flows into such intimate contact with the flanges and the wall of the cover as to effectually seal 85 the joint against passage of air under atmospheric pressure, or under any unbalance between atmospheric pressure and the pressure within the box due to cooling. The inner flange D is made of sufficient height to 90 permit the body of molten lead to rise under excessive pressure on the outside, without overflowing the flange. Under this method of procedure and with the described apparatus or apparatus equivalent thereto, air 95 might escape when unduly expanded within the box, by bubbling through the molten lead or other sealing material, but I prefer to use a vent E located at a suitable point 100 in the cover constructed as shown in the form of a trap with overlapping concentric walls on the two parts and with the wall E¹ on the cap dipping into a trough E² on the box within which is lead or other sealing material that becomes fluid under heat. 110 Under excess of pressure, the flange of the cap rises out of the lead to permit escape of

air, but during cooling, the cap closes under the excess of external pressure and prevents return of air to the box.

For convenience in manipulation, and to leave the box in readiness for use at all times when the sealing medium is cooled, means are provided to remove the sealing medium from the trough. This may be done in the act of removing the cover to open the box as by adapting the cover to lift the body of sealing material which has become molded in the trough, by providing openings B^1 in the lower edge of the cover into which the sealing material flows to rivet the body of material to the cover, or by providing an enlargement B^2 at the lower edge of the cover so that it will lift the body of sealing material with it; or both these lifting means B^1 and B^2 , or the removal of the sealing medium from the trough may be accomplished by having an additional trough or receptacle F of sufficient capacity to contain the sealing medium, and communicating with the trough through an opening F^1 having a lute or stopper of clay or equivalent material that may be readily removed, when it is desired to remove the sealing medium, the latter being independently heated so that it will flow.

I do not limit myself to the use of lead as the sealing material but may employ fusible salts of metals that will become fluid at a sufficiently low temperature and will not volatilize under the temperature to which the annealing box must be subjected in use.

The tray is preferably provided at the bottom of the trough, with transverse ribs A^1 which support the cover slightly above the bottom and permit molten lead or other sealing material to flow from one side to the other.

G represents a layer of sand or other powdered or pulverulent material placed upon the sealing body of lead to reduce drossing or oxidizing of the metal.

As will be seen from the drawings, the pan or tray may be substantially flat with the walls of the trough projecting above its general plane, as shown in Figs. 1 to 4, or it may be constructed with the trough dropped below its upper surface a' .

When embodying the latter construction, the trough may provide the support for the tray and the tray may be hollowed out as shown at a for the sake of lightness and economy of construction. Or, if preferred, the tray, in addition to having the elevated supporting surface a^1 and the shallow under side a , may be elevated as a whole, to provide for circulation of air beneath it. To accomplish this latter purpose, I provide the pan or tray with a series of transverse strengthening ribs a^2 extending across the hollow under side and a suitable number of supporting feet a^3 , preferably of slightly

greater thickness than the strengthening ribs a^2 and having such increase of thickness of those feet which are beneath the supporting surface of the tray, extending all the way up to the bottom wall.

Having thus described my invention, what I claim as new therein, and desire to secure by Letters Patent is:—

1. An annealing box comprising a tray having an annular trough; a cover to rest in said trough; and a seal to close the joint of said cover and tray consisting of a metal which flows at a temperature less than the maximum annealing heat. 75

2. An annealing box comprising a tray having an annular trough adapted to hold a fusible seal and a cover to rest in said trough; one of these members being constructed with its opposite faces inclined to the overlapping portion of the other member 85 and to each other whereby it facilitates separation of the sealing medium from said member.

3. An annealing box comprising a tray having an annular trough, and a cover to rest in said trough; said trough being adapted to hold a seal; and the walls of one of these members being tapered to facilitate separation of the sealing medium from said walls and the walls of the other member being 95 constructed to induce adhesion of the sealing medium when cold.

4. A seal for hermetically closing the joint between parts of annealing or other like apparatus comprising a trough formed 100 on one part and a wall carried by the other part and said trough being adapted to confine a sealing medium that is fluid under a temperature lower than that at which the process is carried on and one of the parts 105 with which the sealing medium contacts, being constructed to cause the sealing medium to interlock therewith on cooling.

5. An annealing box consisting of a tray constructed with inner and outer walls forming a trough and a cover constructed with a lower edge adapted to enter said trough; said box being provided with means for removing a sealing material from the trough. 110

6. An annealing box comprising the tray constructed with a trough, a cover having its wall constructed to enter said trough, and means on said cover for removing a sealing medium. 115

7. An annealing box comprising a tray 120 constructed to confine a sealing medium and a cover having its wall fitted to said tray and constructed with recesses to engage a sealing medium for lifting the latter from the tray.

8. An annealing box comprising a tray constructed to confine a sealing medium and a cover having its wall fitted to said tray and constructed with recesses to engage a sealing medium for lifting the latter from the 130

tray, said recesses consisting of openings through the wall of the cover.

9. An annealing box comprising a tray, a metal that becomes fluid at a temperature less than the annealing heat, confined by said tray, and a cover dipping within the surface of the sealing medium when in fluid state.

10. In an annealing box the combination of a tray having a trough and a cover having secured to its lower edge, a body of material adapted to enter said trough and which becomes fluid under the influence of heat.

15. 11. In an annealing box, a vent consisting of overlapping walls and a sealing material that becomes molten on the application of heat.

12. In an annealing box a vent consisting 20 of a cap, the overlapping wall of the annealing box and a sealing material confined between said parts, that is fluid under the annealing heat.

13. In an annealing box, a vent comprising 25 an opening in the box surrounded by a trough, a cap having a flange or wall entering the trough, and a sealing material in the trough that is fluid in the annealing heat.

14. An annealing box having a surrounding 30 trough and having its supporting surface elevated to a plane above the trough.

15. An annealing box having its tray constructed with a surrounding trough extend-

ing below the plane of the upper surface of the tray and having the under side of the 35 tray constructed with a hollow space to reduce the thickness of the bottom wall of the tray.

16. An annealing box having its tray constructed with a surrounding trough, extending below the plane of the bottom of the tray and with a hollow under side having 40 transverse strengthening ribs.

17. In an annealing box, a tray having a surrounding trough, a hollow under side and 45 supporting feet elevating the tray and permitting the circulation of air beneath it.

18. An annealing box having a tray constructed with a surrounding trough and with transverse strengthening ribs and supporting 50 feet on its under side.

19. An annealing box having a tray constructed with a surrounding trough and with transverse strengthening ribs and supporting feet on its under side; said trough extending below the surface of the tray, said 55 strengthening ribs extending between the inner walls of the trough, and said supporting feet projecting below the ribs.

The foregoing specification signed at Columbus, Ohio this second day of September, 1908.

WILLIAM R. KINNEAR.
